PNEUMATIC EXTERNAL DRAW LAPPLNG
HEAD

Emil H. Brandt, Davenport, Iowa

Application March 21, 1951, Serial No. 216,824

3 Claims. (Cl. 51—184.3)

(Granted under the act of March 3, 1883, as
amended April 30, 1928; 370 O. G. 757)

1

The invention described in the specification and claims may be manufactured and used by or for the Government for governmental purposes without the payment to me of any royalty thereon.

This invention relates to the art of honing or abrading and in particular to devices of the type known as lapping machines.

It is the primary object of this invention to produce a new and improved external polishing head for use on a Barnes draw lapping machine. The Barnes machine referred to herein is a device for abrading cylindrical objects in which the cylinders are held horizontally and turned by the machine structure. A non-rotating abrading head is mounted so that it can be moved along the axis of the machine at the will of an operator. The cylinders are inserted within the head and rotated. The honing head abrades the cylindrical work-piece while the latter rotates and may be moved down the cylinder as desired.

The ordinary draw lapping head in use at the present time contains two abrading stones which can polish only a very restricted surface area at one time. It is accordingly another object of the invention to supply a head containing more than two stones so that a larger area of the work-piece may be treated at one time than is treated now, with consequent saving of time.

Another disadvantage of the present heads is that they depend for the pressure applied to the stones upon springs and wing nuts which can be controlled only by hand and at best with some difficulty. Another object of the invention therefore is to provide a device of the character described controlled more easily than through wing nuts and springs operated by hand. Compressed air is actually the medium of control chosen for my invention.

Another disadvantage of the heads in use now is that removal and replacement of the grinding stones is a rather difficult operation, requiring that the entire upper half of the lapping head be removed. It is consequently still another object of the invention to provide a lapping head which permits the abrading stones to be easily and individually removed and replaced.

Other objects of the invention will be evident from the following description and the appended drawings in which:

Fig. 1 is an end elevation of my new lapping head;

Fig. 2 is a sectional view along line 2—2 of Fig. 1;

2

Fig. 3 is a section taken along the line 3—3 of Fig. 2;

Fig. 4 is a side elevation of the new lapping head; and

5 Fig. 5 is a detailed drawing of one section of my apparatus showing a second embodiment.

Described briefly, my invention consists essentially of a hollow relatively long retaining cylinder adapted to fit around a cylindrical workpiece 10 held in the Barnes machine. Symmetrically positioned above this retaining cylinder are two pneumatic cylinders, each actuating a lazy tongs. Upon the retaining cylinder are mounted two collars which have a limited sliding movement 15 upon the cylinder. The collars are controlled by the free ends of the lazy tongs. Within the retaining cylinder are positioned abrading stones held in place by detachable springs. Movable keys contact the stones and extend through the 20 retaining cylinder. The movable keys make external contact with bevels in the slidable collars. Consequently motion of the collars, caused by the lazy tongs and the pneumatic control of the tongs, is transmitted to the abrading stones in 25 opposition to the force of the positioning springs. Any desired pressure can thus be applied very simply to the stones.

Referring now more particularly to the drawings, a workpiece 10 is shown engaged in a retaining cylinder 12 by abrading stones 14 set in backing plates 16. Eight such backing plates are 30 evident in the embodiment of the invention illustrated but a greater or lesser number may be used as desired. The backing supports are held tightly against the interior surface of the cylinder 12 by means of detachable springs 18 attached to pins 20 embedded in the cylinder and the reinforcing annuli 22, at the ends of the cylinder. Springs 18 fit into slots 19 cut into the 35 backing plates. Each backing plate carries two abrading stones 14, one at each of its ends. Behind each abrading stone and contacting the backing plate of the stone is a key 24 slidably mounted in a key-way 26 in the ring 28. The 40 rings 28 are mounted in the retaining cylinder 12. The cylinder itself is positioned on the Barnes machine through supports 13.

Slidably held at opposite ends of the retainer cylinder are annular collars 30 and 32. These collars contain bevels 34 on their interior faces contacting the sliding keys 24 and constitute adjusting or control means for the keys. Each bevel is so constructed that it slopes outward towards the end of the retaining cylinder 12 closest its 55 respective collar. Each of the collars bears two

trunnions identified as 36 and 38 located at diametrically opposite points on its external surface. Through these trunnions connection is made with a free end of each of two lazy tongs, 40 and 41.

Lazy tongs 40 consists of two long bars, 42 and 44, and two short bars, 46 and 48. The longer bars pivot at one of their ends at a fork 54. The free end of bar 42 is connected through trunnion 36 to collar 30. The free end of the other long bar, 44, is in similar fashion connected to collar 32. The shorter bars 46 and 48 are pivoted together at one of their ends by a pivot 15 located half way along the length of the retaining cylinder 12. The free end of bar 46 is pivoted at a point 47 about halfway along bar 42 while the free end of bar 48 is in the same manner pivoted at point 49 to bar 44. While only lazy tongs 40 has been described, lazy tongs 41 is of identical construction with connections on the collars 30 and 32 and the cylinder 12 diametrically opposite the connections of tongs 40. However while lazy tongs 40 is pivoted at fork 54, lazy tongs 41 is pivoted at fork 55. The two tongs of course parallel each other along opposite sides of the cylinder 12.

The two forks 54 and 55 are connected through piston rods 52 and 53 to small conventional pneumatic cylinders 50 and 51. Details of one of these cylinders can be seen in Figure 2. The piston rod 52 connects fork 54 and piston 56, entering cylinder 50 through bushing 57. Spring 58 supplies a force opposite that of the compressed air entering through conduit 62. Rings 59 and 60 supply packing for the piston. Externally each cylinder carries flanges 64 fastened in any convenient manner to a supporting standard 66. Standard 66 is mounted rigidly on cylinder 12 and consequently holds the pneumatic cylinders in proper fixed positions relative to the other parts of the apparatus.

Various modifications lie within the scope of my invention. Figure 5 shows one such modification in which the sliding key 24' is made integral with the stone backing support 16. In this embodiment the springs 18 are relieved of some strain in that the keys now give longitudinal support to the backing plates.

The operation of the device is obvious from the description. The new and improved abrading head is substituted on the lapping machine for the hand controlled head now in use. A work piece is rotatably mounted in this head and the abrading operation is carried out as normally performed. As far as the head itself is concerned, an operator merely controls by hand the pressure on the pneumatic cylinder from a valve not shown in the drawings. This pressure is transmitted through the lazy tongs to the movable collars and the sliding keys which actuate the grinding stones, the camming action of the bevels changing the longitudinal motion of the collars a radial movement of the keys. Increasing the pressure in the pneumatic cylinders opens the pair of lazy tongs, drives the bevels outward, and through the keys increases the pressure on the stones. Removal of pressure on the keys permits the restoring force of the springs holding the backing plates to operate. The pressure applied to the stones can consequently be regulated within desired limits.

The stones are very easily removed from or replaced in my lapping head. It is only neces-

sary to loosen the tension on the retaining springs or slip the spring out on its slot and over the end of the backing plates. One or more plates can be replaced at a time without taking the entire head to pieces. The objects of the invention have therefore been achieved by the device described. I do not however desire to be bound strictly by this description but solely by the scope of the appended claims.

I claim:

1. A lapping head for abrading a cylindrical work-piece comprising a hollow retaining cylinder carrying internally abrading means adapted to engage said work-piece, springs resiliently holding said abrading means within said cylinder, keys slidably extending through key-ways in the cylinder and making contact with the abrading means, said key-ways being spaced in two groups circularly around the circumference of said cylinder, one of said groups being located a predetermined distance from one end of said cylinder and the other of said groups being located the same predetermined distance from the other end of said cylinder, a slidable annular collar around each of said key-ways, a bevel on the inner surface of each annular collar making slidable angular contact with the keys extending through said key-ways, two lazy tongs extending parallel to each other lengthwise along the sides of the cylinder pivotally connected to said cylinder and attached to the collars at points thereon diametrically opposite each other, each of said lazy tongs consisting of two relatively longer bars, pivoted at a junction at one of their respective ends and pivoted separately to one of the collars at the other of their ends, and of two relatively shorter bars, pivoted together to the cylinder at one of their respective ends and pivotally connected separately at the other of their ends to corresponding points along the length of the relatively longer bars, and means for imparting rectilinear motion the junction point of the two relatively longer bars in a direction perpendicular to the axis of said retaining cylinder whereby, through the action of the lazy tongs, the annular collars are slidably moved in opposite directions along the cylinder in such a manner as to urge, through the sliding keys, the abrading means against the springs when the collars moving towards the respectively nearer ends of said cylinder.

2. The lapping head of claim 1 in which the means for imparting rectilinear motion to the junction point of the relatively longer bars is a hand-controlled hydraulic piston.

3. The lapping head of claim 2 possessing a separate hydraulic piston for each lazy tongs, the two pistons being synchronously controlled to ensure cooperative action of the two lazy tongs.
